AIR CONDITIONING APPARATUS

William B. Whitsitt, Baltimore, Md.

Application March 11, 1932, Serial No. 598,260

10 Claims.

(Cl. 62—117)

This invention relates to a method of and apparatus for condensing the heat laden vapor of a refrigerant used in a cooling system, such as an air conditioning system or other cooling system, 5 to liquefy or condense the refrigerant for continued use, and particularly to a condensing method and apparatus especially designed and adapted for use in the air conditioning systems of railway passenger cars and the like.

10 One object of the invention is to provide a condensing method and apparatus whereby and wherein the condenser containing the refrigerant is subject to the cooling influence of countercurrents of water and air in such manner as to 15 secure a maximum heat-exchange action within a minimum period of time and a rapid condensation of the refrigerant.

Another object is to provide a condensing method and apparatus whereby a compact type of condensing apparatus may be used, which allows 20 cooling water in small volume to be employed, and which effects the simultaneous cooling of the condenser and the water, whereby the water may be used over and over again and without previous 25 cooling other than that effected by the condenser.

Still another object of the invention is to provide a condensing method and apparatus employing a novel countercurrent principle for effecting a heat-exchange action by the passage 30 of a current of air in a diffused state upwardly through a fog-like atmosphere in the form of a descending current of water vapor of substantially uniform density, whereby a heat-exchange action of highest efficiency and great rapidity is 35 obtained to effect the condensation of the refrigerant in a minimum period of time and in greater volume than heretofore possible within a given period of time.

Still another object of the invention is to provide a condensing method and apparatus which by reason of its high efficiency and simplicity and compactness of the apparatus required is particularly adapted for use in the air conditioning systems of passenger cars so as to permit a 40 non-toxic volatile refrigerant to be employed, with the advantage of enabling such refrigerant to be expanded in and employed to directly cool the air cooling coil, and with the further advantage of materially reducing the number of working parts in such systems and the cost of installing and maintaining the same in repair, as well as other substantial advantages, as will more fully 45 hereinabove appear.

With these and other objects in view, the invention consists of the features of construction,

combination and arrangement of parts, herein-after fully described and claimed, reference being had to the accompanying drawings, in which:

Fig. 1 is a diagrammatic top plan view of a railway car or coach showing the application of an apparatus embodying the invention thereto.

Fig. 2 is a side elevation of the same.

Fig. 3 is a view partly in end elevation and partly in vertical transverse section through the car shown in Figs. 1 and 2.

Fig. 4 is a plan view of a portion of the car showing the compressor and its driving motor and refrigerant and water circulating pipes beneath the car body and the combined cooling tower and refrigerant condenser at one end of the car.

Fig. 5 is a vertical transverse section taken substantially on line 5—5 of Fig. 4.

Fig. 6 is a side elevation of the combined cooling tower and refrigerant condenser.

Fig. 7 is a vertical section of the same.

Fig. 8 is a sectional plan view of the combined cooling tower and refrigerant condenser.

Fig. 9 is a diagrammatic perspective view of the working parts of the apparatus.

Fig. 10 is a horizontal section through the air cooling compartment of the car.

Referring now more particularly to the drawings, the car 1, of coach or other type, one of coach type being herein shown merely for purpose of exemplification, is provided with the double-sashed windows 2 which are designed to remain continuously closed while the air conditioning apparatus is in operation in order to prevent entrance of dust, soot, cinders and other foreign matter and contamination of the conditioned air by any direct admixture of external air carrying such impurities therewith. Extending longitudinally at one side of the passenger space of the car is a distributing duct 3 having air distributing outlets 4 at intervals in its length, through which duct and its outlets conditioned air from a conditioning compartment 5 is continuously supplied to the passenger space. This compartment 5 is preferably located at one end of the car in the half-deck or roof zone and is provided with a suitably controlled fresh-air inlet 6, and is in communication with the passenger space 7 through an air return grille 8, whereby the air may be continuously re-circulated between the passenger space and conditioning compartment and mixed with fresh air admitted through the inlet 6 whenever desired or required. If desired, a filter of suitable type may be employed to remove all foreign impurities from the fresh air entering through inlet 6. Manually-operated ventilators 55

9 may be provided at the side of the car opposite the duct 3 for ventilating purposes in case the air conditioning apparatus of the car should at any time become inoperative. In the compartment 5 is a coil 10, forming a surface cooler over which the air to be cooled and conditioned is passed, and which, in accordance with my present invention, is designed to be cooled by the expansion and heat-absorbing action therein of a volatile refrigerant. An air fan or drum 11, driven by an electric motor 12, draws air by suction through the inlet 8 (and inlet 6 when open) at one side of the car into the compartment 5 and across said compartment and over the cooler 10, whereby the air is cooled and de-humidified, and the fan or drum 11 then discharges the so conditioned air under pressure into the duct for delivery to the passenger space of the car. By recirculating the air and re-conditioning it as to temperature and humidity the passenger space 1 may be kept at any desirable temperature below outside atmospheric temperature, and by admitting fresh air when required through the inlet 6 the internal air may be kept in a wholesome condition. The distributing duct and coating parts of the distributing mechanism are so constructed as to effect the circulation of the air in such manner as to avoid the creation of objectionable drafts. The parts so far described may comply generally in structure and arrangement with corresponding parts disclosed in my prior application filed May 4, 1931, Serial No. 534,995, or they may be of any other suitable equivalent structure and arrangement for combinative co-action with parts hereinafter described to secure the aforesaid advantages obtained by my invention. By arranging the air cooling compartment so that it extends transversely the major portion of the distance between the opposite sides of the car, instead of longitudinally of the car, provision is made for employing a cooling compartment of greater length and a cooling coil also of a greater length or of a greater number of coiled sections than is otherwise possible without extending such compartment inwardly and over the main passenger containing space of the car, while at the same time obtaining a longer range of travel of the air while it is being cooled by the cooler and a greater extent of cooling surface, so that a larger amount of air may be cooled within the compartment during a given time period in the travel of the circulating air than is possible by the use of cooling compartments and coils of the character heretofore employed in air conditioning apparatus for cars.

My improved air conditioning apparatus embodies, in addition to the above-described conditioning unit, a refrigerant unit employing a non-toxic volatile refrigerant and comprising a refrigerant compressor 11', an electric motor 12' for driving the same, a cooling tower or condenser chamber or casing 13 enclosing a refrigerant condenser comprising coils 14 and 15 for cooling the refrigerant condenser water and condensing the refrigerant, a pump 16 for circulating the cooling water, and a motor 17 for driving said pump, together with coating parts, as hereinafter described, for carrying such cooling and condensing actions into practical operation.

The non-toxic refrigerant employed is preferably dichlorodifluoromethane, commercially known as F-12, which may be directly expanded in the air cooling coil 10 for cooling the same without liability of rendering the air toxic or otherwise injurious to human life or liability of caus-

ing toxic effects or physical discomfort to passengers in the event of leakage of a greater or less quantity of the refrigerant from its circulatory system into the air stream due to ordinary causes or accidents.

The gaseous refrigerant compressed by the compressor 11' is forced thereby into a feed pipe 18, which extends therefrom to the tower 13 and upwardly through the bottom of the tower to a cross pipe 19 connecting the upper ends of the refrigerant cooling and condensing coils 14 and 15 contained therein, the refrigerant passing downwardly through said coils to a cross pipe 20 connecting the lower ends of the coils, from which the cooled and condensed or liquefied refrigerant flows through a discharge pipe 21 to a float type of expansion valve 22. This float valve is located directly beneath the condenser casing or cooling tower and operates to expand the liquid refrigerant, which is under a pressure of about 125 pounds, and to allow the expanded refrigerant to pass through a delivery or expansion pipe 23 to the cooling coil 10.

The refrigerant in expanding and passing through the cooling coil 10 cools such coil to a desired degree so as to effect the cooling of the circulating air flowing over the surface of the coil to the desired degree, the expanded and heat laden refrigerant then being drawn by the action of the compressor 11' back to said compressor 30 through the suction pipe 24 and compressed again for delivery through the pipe 18 to the refrigerant condenser for re-liquefaction. The air flowing over the coil 10 and cooled to the desired degree is also re-dehumidified or deprived of a portion of its moisture, and in such condition is delivered through the duct 3 into the passenger space of the car. It will thus be seen that the refrigerant or air cooling medium is directly expanded into the cooling coil 10 for a cooling action thereon, and is then returned to the compressor and re-compressed and to the condenser and is re-condensed, and this cycle of action is uniformly continuous as long as the motor 12' is driving the compressor 11' and the action of said compressor is not stopped or otherwise modified or interfered with. Connected to a water chamber in the bottom of the condenser cooling tower 13 is a pipe 26 having a controlling and cut-off valve 27 therein which leads to the cooling jacket of the compressor 11', which in turn is connected by means of a pipe 28 having a controlling and cut-off valve 29 therein with the water circulating pump 16, whereby, if desired, water may be circulated through such pipes and the cooling jacket of the compressor to keep the compressor cool. The use of these pipes 26 and 28 is, however, optional and may in many cases be dispensed with, since in the use of the non-toxic refrigerant, such as F-12, with a water cooled condenser of the novel type herein disclosed, the usual operating head pressure is reduced to about 120 pounds, and the corresponding operating temperature is reduced to about 125° F., so that the use of cooling water in the compressor jacket is not essential.

Entering the cooling tower, at a point about midway of its height, is a water feed pipe 30 through which water is forced from the pump 16 to a distributing pipe 31 which conducts it to 70 spray nozzles 32, having openings for discharging small fan-like jets of water at different levels in a finely atomized condition over the refrigerant condensing pipes or coils 14 and 15, which jets commingle to form a dense, fog-like cooling cur-

rent of atomized water traveling downward in the condenser chamber. Located at one side of the cooling tower adjacent the bottom thereof is an air inlet 33 provided with screen baffles 34, through which inlet air is drawn by a suction and discharge fan 35, mounted in the top of the tower, for upward travel from said inlet to the top of the tower and finally out through a discharge outlet 36. The function of these baffles 34 is to filter out foreign particles traveling with the air and to reduce the velocity of the air to a suitable degree and to divide the air into a multiplicity of streams, whereby the air is caused to enter the tower in a diffused state instead of in a concentrated state or in the form of a blast. This air in its upward travel comes in contact with the highly atomized spray water delivered from the spray nozzles and rapidly cools the water particles by direct contact therewith and, in flowing upward over the surfaces of the condenser coils 14 and 15, causes the water particles on the surfaces of said coils to evaporate, thereby effecting a rapid cooling and liquefaction of the refrigerant in the coils. The air after passing through the water current of atomized water flows through a suitable type of eliminator 37, which acts as a baffle to check and prevent unduly rapid upward flow of the air and removes any moisture contained in the air which flows back into the water supply chamber at the bottom of the tower. An electrical motor 38 disposed in the top of the tower drives the fan 35. It will thus be seen that the cooling tower condenser 13 serves the double purpose of cooling and liquefying the refrigerant in the condensing coils 14 and 15, and at the same time cools the water employed for the coil cooling action, thus entirely doing away with the necessity of using a separate and independent pump, motor, brine tank, cooling coils and associated piping for cooling brine or fresh water to be used to cool the condenser coil and also for cooling and supplying brine or water to cool the air cooling coil 10, such as are necessary where anhydrous ammonia, for example, is employed as a primary refrigerant to cool water or brine which is to be used to cool the coil 10 in place of the direct use of ammonia, in order to avoid its dangerous use as a direct cooling agent for the air cooling coil.

50 A float valve 39, located at the bottom of the condenser cooling tower, is provided to maintain a constant water level in the water chamber at the bottom of such tower in order to constantly provide the necessary suction head to the circulating pump 16 supplied with water therefrom through pipe 41. This water is supplied from a storage tank or reservoir 40 suitably supported adjacent the tower at the end of the car through a valved pipe connection 41' leading to said water chamber.

The types of air conditioning apparatus heretofore used for air conditioning the passenger space of a passenger vehicle have generally been designed to employ ice as a primary refrigerant or anhydrous ammonia or other toxic primary refrigerant operating at comparatively high temperatures and pressures. As ice as used can not be directly employed for cooling the air cooler and as such toxic refrigerant can not be directly expanded for the air conditioning effect in the air cooler, because of the possibility of its leakage into the circulating air stream, with liability of danger to the occupants of the vehicle, it has been necessary in both cases to use the primary refrigerant to directly or indirectly cool a sec-

ondary refrigerant, such as water, which is circulated through a circulatory system including the cooling coil to temperature the latter for the air cooling action. These types of apparatus, therefore, require the use of complex piping in 5 addition to separate means for circulating the cooling water and primary refrigerant and in the case of a volatile refrigerant means for cooling the latter, and also requires a lengthy course of travel for the cooling water and the location 10 of the condenser employed in a volatile refrigerant system as well as the driving motor, the pumps, and the compressor on the underside of the vehicle, where they are exposed to the action 15 of the elements and liability of damage by contact with extraneous objects. Furthermore, such indirect types of apparatus are costly in construction, operation and maintenance, because of the number of units employed, and the relatively intense refrigerating effect produced by the character 20 of refrigerant used in systems using a volatile refrigerant, renders such a system difficult to control in order to prevent undue cooling of the air, so that a complex system of control devices must be employed to regulate the working operation 25 of the working parts to produce constantly uniform cooling and conditioning actions.

In prior systems of this character it has also been necessary, because of the large number of working parts to be driven, to employ an electric 30 generator of at least 12½ H. P., to furnish the amount of current necessary for power purposes, and such generators have been ineffective for service action unless the train is running at a speed of twenty-five miles or more per hour and, 35 for this and other reasons, such generators are incapable of furnishing sufficient current for storage to enable the working parts of the air conditioning system to be driven when the train is standing in a yard or at stations, so that the 40 efficiency of the air conditioning system is greatly impaired and reduced and greater work thrown upon the system when the train is running than would otherwise be the case.

My invention has been designed to overcome 45 these objections to prior apparatus of the character named and to enable a volatile refrigerant which may be of less intensive heat absorbing qualities than others but of safe (non-toxic) character to be used with great efficiency for 50 directly cooling the cooling coil, thereby obviating the necessity of using a refrigerant of toxic character or a second refrigerant and its circulatory system, as well as to enable the refrigerant cooling and condensing means to be compactly 55 disposed within the vehicle outside the course of circulation of the circulating air but close to the conditioning compartment, with the result of reducing liability of leakage of any of the refrigerant into the circulating air as well as reducing 60 the extent of travel of the liquefied refrigerant so as to secure maximum efficiency of action thereof and other advantages.

The direct use of a non-toxic volatile refrigerant in a reliable, economical and efficient manner, however, involves certain problems requiring satisfactory solution, to wit, not only the selection of a refrigerant having the dual requisites of being of harmless character and capable of being operated at a low operating head pressure and a 65 low operating temperature, which are factors of importance not only in securing a highly efficient condenser cooling action in a simple and compact structure, but also in providing condensing means for securing such a coordination in the actions 70 75

of the air cooler and condenser cooling means that satisfactory relative cooling actions of the air cooler and condenser may be obtained. It is desirable, if not essential, for instance, to increase the cooling area of the coil to secure the proper cooling of the air, in the use of a refrigerant of this character, and it is also highly desirable, if not essential, to provide for the cooling of the condenser in a rapid and very economical manner and by means compact enough to be disposed within the vehicle and preferably in close proximity to the conditioning compartment. The desirability for such highly efficient separate and conjoint cooling actions and cooling coactions will be readily evident from the fact that, because of the large size of passenger vehicles used in this country and the widely varying outside atmospheric temperatures met in the travel of a train, as well as the necessity of taking care of internal temperature modifying conditions, as in a dining car, the cooling means must be adequate to cool the large volume of circulating air in the vehicle and the condenser action must be correspondingly adequate to properly condition the refrigerant in its cycle of operation, which have required a novel and peculiar construction, proportioning and working coaction of the parts in order to meet these working requirements and to enable the majority of working parts to be disposed inside the vehicle.

Because of its noted properties I have found dichlorodifluoromethane (F-12) to be a satisfactory non-toxic volatile refrigerant, although possibly others may be used without alteration, or by slight alteration, of the mechanism employed. In order to obtain the most efficient use of this refrigerant, with proper regard to its heat-absorbing properties, I preferably dispose the air cooling coil 10 in a compartment 5 which extends transversely of the car, that is, has its inlet at one side of the car and its outlet at the opposite side of the car, so that a cooling coil of larger cooling area may be used and a longer range of travel of air in contact therewith secured within the restricted space available in the vehicle and without encroaching upon the head space of the passenger compartment or undesirably modifying the conventional structure of the car. By this means provision is made for cooling and dehydrating the air in the large volume required by the use of a refrigerant of the character described.

In order to be able to place the condenser close to the air cooling compartment and in the confined space within the car available for that purpose, which location of the condenser is desirable under many conditions, the condenser necessarily must be of restricted size, and therefore, and for the purpose of conserving cooling water, a highly efficient condensing action thereof is essential so that it may handle the comparatively large volume of compressed heat-laden vapor passing thereto from the comparatively large sized cooling coil. A most effective heat-transfer action between the condenser coils, condenser cooling water and the cooling current of air passing therethrough must be obtained, which is secured by a novel construction and arrangement of parts and heat-exchange action between the condenser coils, cooling water and cooling air current in the following manner. It will be observed that by the arrangement of the jet devices 32 at different levels the finely atomized streams of water projected therefrom will be distributed over a wide area within the condensing chamber and com-

mingled so as to form a body or column of finely divided water particles or fog like atmosphere which, through the force of gravity, travels downward in the condenser chamber toward the water collecting chamber at the bottom of the tower. Through this descending column of finely atomized water travels the stream of air drawn by the suction of the fan 35 through the air inlets 33. The baffles 34 at this point operate to divide up the air stream into finer streams and act as retarders to prevent too rapid inrush of the air and to diffuse the air as it enters throughout the entire area of the chamber. This body or column of air in its travel upwardly through the descending column of atomized water acts to check the downflow of the water particles, so that the very minute streams of air in traveling upward come in contact with all sides or all portions of the water particles for a heat exchange action. The upward travel of the air drawn by the suction fan through the water vapor body composed of commingled streams of atomized water in the condensing chamber is further retarded by the action of the separator baffles 37, so that any forcible upward rush of the air through the cooling water vapor, or travel of the air in concentrated form or great velocity, is further prevented and the body of air caused to flow in a diffused condition upwardly at an even and regulated rate of travel before discharging through the outlet 36. By reason of the fact that the descending particles of water are caused in this manner to meet upflowing streams of a body or current of diffused air moving at an even and regulated rate of speed, the water particles are held in a state of suspension long enough to increase their time period of contact with the air and an agitation of the water particles is caused due to their tendency to be carried up by the air and tendency to fall by gravity, so that a sort of washing action is instituted through a time period of contact which ensures a maximum degree of heat exchange action between the two fluids, whereby the cooling water is cooled to the highest possible degree. This prolonged time period of contact between the water and air occurs through the entire effective height of the condensing chamber utilized for the cooling action, giving such a lengthy period of travel and intimacy of contact of the cooling elements that the highest possible degree of cooling action of the air on the water is obtained, such as would be impossible under other than a countercurrent action. As the air in its upward travel flows along the surfaces of the coils in contact with the water flowing down over the coils a direct cooling effect on the coils is caused by evaporation of the water so that a rapid and intensified heat exchange action is obtained. By employing a counter-current cooling action of the air and water in the manner described, and by discharging streams of the water at different levels, so as to create successively cooling zones through which the air passes, whereby the cooling action is still further increased, it is possible to furnish a condenser which is sufficiently small and compact to be mounted within the car above the floor level and which has such a degree of cooling efficiency as to cool and condense the refrigerant vapor in the condenser coils within a comparatively short period of time and with great economy in the use of the water, which is of importance because of the necessity of conserving the supply of water carried by the passenger vehicle. By the use of a surface cooler for the air in the air cooling

compartment which can be made of large cooling area by reason of the transverse arrangement of the compartment, and by constructing a water and air cooled condenser in the manner set forth, 5 a proper coordination or rationing between the heat absorbing action of the surface cooler and the condenser cooling action of the water cooled condenser may be obtained whereby a safe refrigerant directly expanded into the coil may be utilized 10 in a highly efficient manner to condition the large volume of air required for satisfactorily conditioning the passenger space of the vehicle under any and all service conditions.

The efficiency of this condenser in combination 15 with the associated elements of the conditioning system is such that during cool or cold weather a current of outside air alone may be used as the cooling medium, while during warm and hot weather and in warm climates generally resort 20 may be made to the counter-current air and water method of cooling, rendering the condenser suitable for use in all climatic zones and in all seasons of the year in any climatic zone. Also 25 because of the simplified construction and greatly reduced number of parts employed in this system made possible by the efficiency of the condensing means employed it is possible to electrically drive the working parts at a total amperage consumption 30 of 155 at 35 volts, or about 7 H. P., or about one half that required in any other system, with the advantage that the system can be operated 35 from the generator when the car speed is below 25 miles per hour and sufficient current is supplied by the generator to operate the air conditioning system from the battery on the car when the car is standing still in a yard or at stations, thus allowing a car to be pre-cooled before the train starts and the system to be kept in operation at stopping points, which is not possible 40 with other systems.

It will be evident from the foregoing description that as the course of flow of both the refrigerant and the cooling water is short, as compared with prior systems, a less amount of each 45 is required, with a further reduction in piping and increased efficiency of action. Furthermore, conservation of the cooling water supply is also ensured, as, under a suction draw of the cooling air instead of a pressure blast action thereof, the 50 retarding effect of the baffles 37 is sufficient to prevent the discharge of any material amount of water with the outgoing air from the condenser, so that the same water may be used over and over again, with but slight replenishments from 55 time to time, an important consideration in view of the limited space allowed for the carriage of supply water on a car.

From the foregoing description, taken in connection with the drawings, my improved method 60 and apparatus for condensing the refrigerant used in apparatus for conditioning air for passenger cars and the like will be readily understood, and it will be seen that the invention provides a method and apparatus for this purpose 65 which is of extremely simple character and permits of the use of a non-toxic refrigerant as a direct medium for cooling the air cooling coil, without liability of physical discomfort or danger to the occupants of the vehicle in case of ordinary leakage or accidents causing vent or evaporation of a greater or less quantity of the refrigerant directly into the car atmosphere, and which 70 enables simplification of method and apparatus to be obtained and the number of parts reduced 75 so as to considerably decrease the cost of instal-

lation and operation of apparatus of this character. By arranging the fan 11 in the air cooling compartment between the air cooling coil and the air outlet of said compartment a circulation of air through said compartment is effected by 5 the suction action of the fan instead of a forcing action of the fan; in other words, the air is drawn across the compartment by the suction pull of the fan from the outlet side of the compartment, instead of being blown under pressure 10 by the forcing action of the fan across the compartment from the inlet side thereof. By this means the traveling current of air is better diffused and caused to flow more uniformly through the compartment and over the surfaces of the 15 cooling coil, without being under high pressure in such travel and while it is being cooled, so that back-lash of the air, such as would be caused by a concentrated blast from a force fan located at the inlet side of the compartment will be prevented, and the pressure of the air, instead of being checked and reduced by the coil, as in the case of the use of such as force fan, will be maintained substantially constant until the air reaches 20 the outlet side of the compartment, at which time 25 the cooled air will be expelled under a positive force pressure out into the duct leading to the passenger space of the car, so that a more positive and reliable circulation of the air will be ensured. The simplicity of the structure and relatively 30 small number of parts employed adapts the working parts to be driven by the electrical supply equipment of a passenger car with greater surety of continuous action and without danger of overloading. 35

What I claim is:—

1. In an air conditioning apparatus for passenger vehicles having a passenger compartment, an air conditioning compartment, means for circulating air between said compartments, an air conditioning system employing a non-toxic volatile refrigerant condensable at a low operating head pressure and temperature and including an air cooling coil in the conditioning compartment in which the refrigerant is directly expanded to effect the cooling of the air in said chamber, a compressor for compressing the heat laden vapor resulting from the expansion of the refrigerant in said coil, and a condenser for liquefying the refrigerant for reuse in the coil, the said condenser comprising a chamber, a condensing coil enclosed in said chamber, means for producing and subjecting the condensing coil in the chamber to the cooling action of a cooling atmosphere of substantially uniform density formed by commingled sprays of water in a finely atomized state traveling as a current downwardly in the chamber and over the surface of the condenser coil, suction means for producing in said chamber a cooling countercurrent of air and drawing the 60 same upwardly in contact with the condensing coil and throughout the current of atomized water, and governing means for diffusing the air and controlling its rate of speed so as to cause an intimate intermingling of the particles of air and 65 water and a suspension of the water particles in the air and to retard the downflow of the atomized water current whereby to obtain a maximum heat exchange action within a predetermined minimum period of time to effect a simultaneous 70 cooling of the water and the condensing coil. 75

2. In an air conditioning apparatus for passenger vehicles having a passenger compartment, an air conditioning compartment, means for circulating air between said compartments, an air con-

- ditioning system employing a non-toxic volatile refrigerant condensable at a low operating pressure and temperature and including an air cooling coil in the conditioning compartment in which the refrigerant is directly expanded to effect the cooling of the air in said chamber, a compressor for compressing the heat laden vapor resulting from the expansion of the refrigerant in said coil, and a condenser for liquefying the refrigerant for reuse in the coil, said condenser comprising a water tower, a condensing coil enclosed therein, and means for producing and subjecting the condensing coil in the tower to the cooling action of a downwardly traveling current of water in a finely atomized state and a suction drawn countercurrent of diffused air passing upwardly through said atomized water current.
3. In an air conditioning apparatus for passenger vehicles having a passenger compartment, an air conditioning compartment, means for circulating air between said compartments, an air conditioning system employing a non-toxic volatile refrigerant condensable at a low pressure and temperature and including an air cooling coil in the conditioning compartment in which the refrigerant is directly expanded to effect the cooling of the air in said chamber, a compressor for compressing the heat laden vapor resulting from the expansion of the refrigerant in said coil, and a condenser for liquefying the refrigerant for reuse in the coil, the said condenser comprising a chamber having an air inlet at or near its bottom and an air outlet at or near its top, a condensing coil disposed in said chamber, means within the chamber for producing a cooling atmosphere of water in a finely atomized state traveling as a current downwardly therein and over the surface of the condensing coil, a suction device at the top of the chamber for drawing a countercurrent of air through the air inlet and upwardly in the chamber in contact with the condensing coil and through and in intimate contact with the particles of the atomized water, baffles at the air inlet for dividing the entering air into a plurality of streams so that the entered air on commingling will be drawn upwardly through the descending atomized water current in a diffused state, and baffles at the top of the chamber between the condenser and suction device for maintaining the diffused condition of the air, governing its rate of flow through the atomized water current and straining from the discharging air moisture tending to be drawn outward therewith.
4. In an air conditioning apparatus for passenger vehicles having a passenger compartment, an air conditioning compartment, means for circulating air between said compartments, an air conditioning system employing a volatile refrigerant and including an air cooling coil in the conditioning compartment in which the refrigerant is expanded to effect the cooling of the air in said chamber, a compressor for compressing the heat laden vapor resulting from the expansion of the refrigerant in said coil, and a condenser for liquefying the refrigerant for reuse in the coil, said condenser comprising a water tower, a condensing coil enclosed therein, and means for producing and subjecting the condensing coil in the tower to the cooling action of a downwardly traveling current of water in a finely atomized state and a suction drawn countercurrent of diffused air passing upwardly through said atomized water current.
5. An apparatus for condensing the vapor of

a liquid refrigerant comprising a condenser, a water tower containing the condenser and having an air inlet at or near its bottom and an air outlet at or near its top, water injecting means within the tower for producing a uniform atmosphere of highly atomized water traveling as a current downwardly therein and over the surface of the condenser, a suction device at the top of the tower for drawing a countercurrent of air through the air inlet and upwardly in the tower in contact with the condenser and directly through the atomized water current, baffles at the air inlet of the tower for diffusing the entering air, and baffles in the top of the tower between the condenser and suction device for retarding and controlling the speed of travel of the air through the atomized water current and straining moisture from the air.

6. An apparatus for condensing a refrigerant comprising a water tower having an air inlet at or near its bottom and an air outlet at or near its top, a condenser disposed therein and embodying horizontally spaced vertical coils located at opposite sides of the tower, a water spraying means located in the tower in the space between the coils and embodying a plurality of injectors arranged at different levels for injecting into said space sprays of water in a highly atomized state so as to commingle and form a cooling current traveling downwardly in the tower about and over the surfaces of the condenser coils and directly upward through the atomized water current, baffles at the air inlet of the tower for diffusing the entering air, and baffles at the top of the tower between the condenser and suction device for retarding and controlling the speed of travel of the air through the atomized water current and straining moisture from the air.

7. An apparatus for condensing a refrigerant used in a cooling system, comprising a water tower having a horizontal transverse air inlet located in one side thereof at or near its bottom and having a horizontal transverse air outlet located in said side at or near its top, a condenser disposed in the tower, means for projecting sprays of highly atomized water at different levels in the height of the tower so as to commingle and form a cooling current traveling downwardly about and over the surfaces of the condenser, a suction device at the top of the tower for drawing a countercurrent of air through said air inlet and about and in contact with the surfaces of the condenser and directly upward through the atomized water current, a plurality of vertically spaced baffles at the air inlet of the tower for diffusing the indrawn air, and a plurality of horizontally spaced baffles at the air outlet of the tower for retarding and controlling the speed of travel of the air through the atomized water current and straining moisture from the air.

8. An apparatus for condensing a refrigerant comprising a condenser, a water tower containing the condenser and having an air inlet at or near its bottom and an air outlet at or near its top, a plurality of injectors arranged within the tower at different levels for projecting therein sprays of highly atomized water commingling to form a current of atomized water traveling downward over the surfaces of the condenser, a suction device at the top of the tower for drawing a countercurrent of air through the air inlet and in contact with the surfaces of the condenser and directly through the atomized water current, baffles at the air inlet of the tower for diffusing the entering air, and baffles at the air outlet of the tower for retarding and controlling the speed of

travel of the air through the atomized water current and straining moisture from the air.

9. An apparatus for condensing a refrigerant comprising a water tower, a condensing coil enclosed therein, and means for producing and subjecting the condensing coil in the tower to the cooling action of a downwardly traveling current of water in a finely atomized state and a suction drawn countercurrent of diffused air passing upwardly through said atomized water current.

10. In an air conditioning apparatus for passenger vehicles having a passenger compartment, an air conditioning compartment, means for circulating air between said compartments, an air conditioning system employing a volatile refrigerant and including an air cooling coil in the con-

ditioning compartment in which the refrigerant is expanded to effect the cooling of the air in said chamber, a compressor for compressing the heat laden vapor resulting from the expansion of the refrigerant in said coil, and a condenser for liquefying the refrigerant for reuse in the coil, said condenser comprising a water chamber, a condensing coil enclosed therein, means for producing and subjecting the condensing coil in the chamber to the cooling action of air, and means for producing and subjecting the condensing coil in the chamber to the cooling action of a downwardly traveling current of water in a finely atomized state.
